(57) **CLAIM**

The ornamental design for a container with lid, as shown and described.

DESCRIPTION

FIG. 1 is a perspective view of a lid portion of the container with lid of FIG. 5 showing our new design.

FIG. 2 is a left side elevation view thereof.

FIG. 3 is a front elevation view thereof.

FIG. 4 is a top plan view thereof.

FIG. 5 is a top perspective view of a container with the lid of FIG. 1.

FIG. 6 is a left side perspective view thereof.

FIG. 7 is a rear elevation view thereof.

FIG. 8 is a front elevation view thereof; and,

FIG. 9 is a top plan view thereof.

The broken lines in FIGS. 6-8 are included for the purpose of illustrating a portion of the container with lid that forms no part of the claimed design.

1 Claim, 6 Drawing Sheets(56)
